US00D675948S

(12) **United States Design Patent**
Kawaguchi et al.

(10) **Patent No.:** US D675,948 S
(45) **Date of Patent:** ** Feb. 12, 2013

(54) **HEAT AND SMOKE DETECTOR**

(75) Inventors: **Koichiro Kawaguchi**, Tokyo (JP);
Hidetaka Irumano, Tokyo (JP);
Manabu Matsumoto, Tokyo (JP);
Masashi Arikawa, Tokyo (JP)

(73) Assignee: **Hochiki Corporation**, Tokyo (JP)

(**) Term: **14 Years**

(21) Appl. No.: **29/387,045**

(22) Filed: **Mar. 8, 2011**

(30) **Foreign Application Priority Data**

Oct. 5, 2010 (JP) 2010-23799

(51) **LOC (9) Cl.** **10-05**

(52) **U.S. Cl.** **D10/106.5**

(58) **Field of Classification Search** D10/106.5;
340/531, 540, 555, 558, 571, 556, 628, 632,
340/640

(57) **CLAIM**

The ornamental design for a heat and smoke detector, as
shown and described.

DESCRIPTION

FIG. 1 is a perspective view of the proposed design.

FIG. 2 is a top plan view of FIG. 1.

FIG. 3 is a front elevation view of FIG. 1.

FIG. 4 is a bottom plan view of FIG. 1.

FIG. 5 is a left side elevation view of FIG. 1.

FIG. 6 is a right side elevation view of FIG. 1; and,

FIG. 7 is a rear elevation view of FIG. 1.

No claim is made to the portions shown in dashed shadow
lines in the images. The interior portions of the item are also
shown in dashed shadow lines and are also not claimed.
Minor opening holes are also not claimed and are shown in
dashed shadow lines. The surface is lined for contour and no
claim is made to the contour designations. The bottom is
unadorned and no claim is made to the bottom surface as the
item is claimed as if on a surface.
